UNITED STATES PATENT OFFICE.

ROBERT WOOD, OF PHILADELPHIA, PENNSYLVANIA.

DESIGN FOR GARDEN-VASE.

Specification forming part of Design No. 5,845, dated May 7, 1872.

Specification describing a Design for "Oval Vases," invented by ROBERT WOOD, of Philadelphia, county of Philadelphia, State of Pennsylvania.

The nature of my design is fully represented in the accompanying photographic illustration, to which reference is made.

What I claim as my invention is—

The oval form, the handles as placed, the ornamentation on rim and body of vase and on pedestal, and the whole general appearance as shown by the illustration.

ROBERT WOOD.
